United States Patent Office

Des. 218,339
Patented Aug. 11, 1970

218,339

PUSH TOY

Ralph W. Crawford, East Aurora, N.Y., assignor to Fisher-
Price Toys, Inc., East Aurora, N.Y., a corporation of
New York

Filed Mar. 6, 1969, Ser. No. 16,093

Term of patent 14 years

Int. Cl. D21—02

U.S. Cl. D34—15

FIG. 1.

FIG. 2.

FIG. 1 is a front perspective view of a push toy showing my new design, and

FIG. 2 is a rear perspective view thereof.

I claim:

The ornamental design for a push toy, substantially as shown.
